Inventor:

H.A. Dirkes

United States Patent Office.

HENRY A. DIRKES, OF NEW YORK, N. Y.

Design No. 3,446, dated April 13, 1869.

DESIGN FOR THE HANDLE OF A TABLE-CASTER.

The Schedule referred to in these Letters Patent and making part of the same.

To all whom it may concern:

Be it known that I, HENRY A. DIRKES, of New York, in the county and State of New York, have invented a new and original Design for Handle of Table-Casters; and I do hereby declare that the following is a full, clear, and exact description thereof, which will enable others skilled in the art to make and use the same, reference being had to the accompanying drawing, forming part of this specification.

The drawing represents a perspective view of my new design for handle of table-casters.

This invention relates to a new design for the handle of table-casters, which is shaped so as to retain a gong or other bell above the supporting-plate of the casters, within a slot or aperture of the handle.

The handle A of the caster has a bifurcated upper

end, forming thereby an opening between the arms *a* *a*, for the gong-bell B, which is supported on the stem of the handle, as shown, or which is otherwise attached to the handle, within the forked upper end of the handle.

The upper ends of the arms *a* are connected by a cross-bar *b*.

Having thus described my invention,

What I claim as new, and desire to secure by Letters Patent, is—

The design for handle of table-casters herein described.

H. A. DIRKES.
